UNITED STATES PATENT OFFICE.

FLOYD S. HARTWELL AND LEONARD C. SEARS, OF ONAWA, IOWA, ASSIGNEES TO MON-
ARCH MANUFACTURING CORPORATION, OF ONAWA, IOWA, A CORPORATION OF
IOWA.

FRAME FOR TILE-MAKING MACHINES.

1,107,940.

Specification of Letters Patent. Patented Aug. 18, 1914.

Application filed May 20, 1912. Serial No. 698,577.

To all whom it may concern:

Be it known that we, FLOYD S. HARTWELL and LEONARD C. SEARS, citizens of the United States, residing at Onawa, in the county of 5 Monona and State of Iowa, have invented new and useful Improvements in Frames for Tile-Making Machines, of which the following is a specification.

This invention relates to improvements in 10 frames for tile making machines, of that type wherein the tile is formed in a jacket by the action of a reciprocatory and rotary packing or forming head, which is driven by a horizontal shaft; and the present application 15 is to be regarded, as to the frame construction, as a division or continuation of the application, Serial No. 650,703, from which our U. S. Letters Patent, No. 1,036, 618, granted August 27, 1912, matured. Tile 20 machines of the type above identified include a vertical shaft which carries the forming or packing head, and which has both reciprocatory and rotary movements, a horizontal shaft to which the power for 25 operation is applied, and connections between the horizontal shaft and the vertical shaft to produce the reciprocatory and rotary movements of the latter. As ordinarily practised, the shafts referred to, and their 30 appurtenant driving mechanism and operating connections, are supported by a frame which comprises a relatively large and heavy superstructure and involves a large number of structural iron parts secured together by 35 a proportionate number of bolt and screw connections. These machines require relatively considerable power for operation, especially in the case of tiles of larger size, owing to the resistance which is opposed to 40 the action of the forming head and to the number and nature of the mechanical connections employed. Furthermore, the reversal of the forming head and the reciprocations of the cement hopper, together with 45 other conditions found in practice and not necessary to detail, produce rapidly succeeding shocks of considerable intensity, which are transmitted to and distributed through the frame of the machine. The result is that 50 after a comparatively short period of use, the bolt connections work loose or become worn, and the rigidity of the superstruc-

ture is correspondingly affected; wherefore it is the case that the alinement of the working parts soon becomes out of true and 55 the ultimate effect is that the forming head does not have a true axially straight movement, but becomes wobbly in its movement and so does not produce a good tile of uniform thickness and true cylindrical contour. 60

The object of the present invention is to avoid the objections stated, and in accomplishing this object, the invention proposes a frame construction of very light and simple nature which may be supported on a 65 pedestal and which is absolutely rigid throughout its extent, involving as it does no bolted connecting parts, struts, braces, or the like. The improved frame construction, although relatively small, furnishes a much 70 more satisfactory and adequate support for the operating parts than the frame construction ordinarily employed; and at the same time provides for ready and quick access to the operating parts for the purposes 75 of renewal or repairs.

An embodiment of the invention is illustrated in the accompanying drawings, wherein:

Figure 1 shows the improved frame construction in its application to the operating parts of the machine; Fig. 2 is a detail side view of the frame construction, with bearing parts removed to show the open bearing members which are rigid and integral parts 85 of the frame; and Fig. 3 is a sectional view on the line 3—3 of Fig. 2.

Similar characters of reference designate corresponding parts throughout the several views.

With the exception of the frame, none of the elements of the machine form the subject of the present application, since they are shown and claimed in our patent referred to. For this reason, these elements are 95 shown only in a general manner in this application, and will be referred to only in a general way.

The forming head is provided at the lower end of a vertical shaft 1, which is rotary and axially reciprocatory. The forming head (which does not appear in the drawings) passes operatively through a tile jacket 2, which rests upon a supporting pal-

let 3. The cement is introduced into the tile jacket through a hopper 4, which comes to rest in an operative position on a bracket 5, and is raised and lowered at intervals, its 5 rising movement enabling the jacket to be lifted from the supporting pallet.

As shown, the shaft 1 is operated both as to its rotating and as to its reciprocating movements from a horizontal shaft 6. The 10 connections for transmitting rotating movement to the shaft 1 comprise miter gears 7, one of which is fixed against rotation on said shaft 1, and the other of which is located at the forward end of the shaft 6; and the connections for transmitting reciprocatory movement to the shaft 1 comprise a worm 8, mounted on the shaft 6, a worm wheel 9, mounted on a transverse shaft 10, an oscillatory beam 11 suitably connected at its forward end to the shaft 1 and supported by a radius link 12, and a link 13 which causes the throw of the beam 11 and is connected to a crank arm 14 on the shaft 10.

The parts referred to and others of ancillary nature are supported, and permanently and securely maintained in operative relation, by a frame indicated generally at 15, and shown in detail in Fig. 2. The frame 15 is of skeleton construction and is 20 integral throughout its extent, all of its parts being disposed substantially in a common vertical plane. The frame has a general rectangular outline, and is altogether devoid of any bolted connections, struts, 25 braces, or the like, or of the necessity for such bolted connections, etc. Aside from the characteristics referred to, the frame is further characterized by the fact that it includes as integral parts thereof open bearing 30 members 16 and 17 for the shafts 1 and 6 respectively. The bearing members 16 are disposed at the front of the frame, extending vertically and preferably facing forwardly and comprise a pair, and the bearing members 35 17 are disposed at intervals throughout the length of the frame, extending horizontally and facing laterally and to the same side of the frame. The complete bearings for the shafts 1 and 6 comprise the members 40 16 and 17 referred to, and bearing caps 18, which are positioned over said shafts and are suitably secured to the respective bearing members. To dismantle the machine as 45 to either or both of the shafts 1 and 6, all that is required is to remove the bearing caps which fit over the shaft or shafts and thereupon the shafts may be taken from 50 position. A similar mode of construction and assemblage is followed as to the shaft 55 10, the latter being fitted in a pair of aligned bearing members 19, which, as shown, are integral with the upper bar of the frame and face upwardly. Bearings for the shaft 60 10 are completed by bearing caps 20, which 65 are similar in all respects to the caps 18.

That portion of the upper bar of the frame upon which the bearing members 19 are formed is itself fashioned as a frame, as at 21, and the bearing members 19 are formed on the respective side bars of the frame portion 21, the worm wheel 9 being disposed 70 between said side bars.

By preference, the bearing members 17 are formed centrally of vertical braces 22, which are integral parts of the frame and 75 extend from the upper to the lower bar thereof. In the construction shown, wherein four of these braces are employed, the intermediate braces converge above the bearing members 17, and meet at one of the bearing members 19, being suitably cut away to accommodate the wheel 9. This arrangement adds greatly to the strength and rigidity of the frame, as is obvious.

Power may be transmitted to the shaft 6 85 from a belt wheel 23 which is loose on said shaft and may be put in operative relation by a clutch 24, or from either of two pinions 25 or 26, the pinion 25 providing for a relatively slow operation of the machine, 90 as when a large tile is to be formed, and the pinion 26 providing for a relatively rapid operation of the machine, as when tiles of smaller diameters are to be formed.

The lower bar of the frame is preferably 95 bulged and tubular throughout the major and central portion of its extent, in the interest of strength and rigidity, and in the embodiment shown, carries at an approximately central point a horizontally disposed 100 annular flange 27, by which the frame may be secured to a supporting pedestal 28. Other means of associating the frame and the pedestal 28 can be employed, in accordance with conditions of work or the choice 105 of the user. The use of the pedestal 28 as a support for the frame 15 has a very substantial advantage in that it eliminates any cumbersome, expensive, and loose superstructure, and the capacity of the frame for this 110 mode of support is regarded as a feature of considerable importance. It will be observed that the construction of the frame with all of its parts in substantially the same vertical plane, coupled with the capacity of 115 the frame for the disposition shown of the operating parts of the machine, causes substantially all the stresses, and certainly all of the most destructive or racking stresses to be exercised in the plane of the frame. 120 The frame may thus be accurately balanced and may be supported securely and immovably upon the pedestal 28, while at the same time, counter-stresses are eliminated, and such stresses as are developed are efficiently 125 resisted, owing to the rigid and integral nature of the frame. The pedestal itself may be used as a support for the bracket 5 and the pallet 3, said bracket and said pallet being jointed to, or forming a part of bracket 130

sleeves 29, which surround the pedestal 28, and may be supported at any desired position thereon.

Having fully described our invention, we 5 claim:

As a machine element, a skeleton generally rectangular supporting frame integral throughout its extent and having all the parts thereof disposed in the same vertical 10 plane, the frame including upper and lower longitudinal bars and a plurality of vertical bars connecting said upper and lower bars, the vertical bars having as integral parts thereof alining open bearing members for a 15 horizontal shaft, which bearing members face toward one side of the machine, the frame also having at its forward end as integral parts thereof forwardly facing open bearing members for a vertical shaft, the

upper bar being formed to provide a frame 20 for a gear wheel and having approximately centrally located open bearing members for the shaft of said gear wheel and the lower bar having on its underside an approximately centrally located horizontal attachment flange, the spaces between certain of 25 said vertical bars serving to accommodate certain gear elements which are mounted on said horizontal shaft, including a gear element which drives said gear wheel. 30

In testimony whereof we have hereunto set our hands in presence of two subscribing witnesses.

FLOYD S. HARTWELL.
